UNITED STATES PATENT OFFICE.

FREDERIK SINDINGCHRISTENSEN, OF NEW YORK, N. Y.

ELECTRIC-ARC LAMP.

SPECIFICATION forming part of Letters Patent No. 769,842, dated September 13, 1904.

Application filed September 29, 1903. Serial No. 175,054. (No model.)

To all whom it may concern:

Be it known that I, FREDERIK SINDING-CHRISTENSEN, a subject of the King of Denmark, residing at New York city, borough of Brooklyn, county of Kings, State of New York, have invented certain new and useful Improvements in Arc-Lamps, of which the following is a specification.

Electric-arc lamps in their simplest form are provided with two carbons, which are usually arranged vertically in the same axial line, and one of said carbons adapted to be moved relatively to the other to strike and maintain the arc.

In my improved arc-lamp two vertically-disposed carbons are employed, each disposed at an angle to the other and adjustable as regards each other, or, preferably, two vertically-disposed angularly-arranged and relatively-adjustable carbons and a third vertically-disposed fixed carbon or other body, which may be rendered incandescent situated between the angularly-arranged adjustable carbons.

The objects of my invention are to decrease the cost of construction, prevent vibration of the carbons and mechanism where an alternating current is employed, do away with the objectionable shadow caused by the usual lower carbon, and where two carbons and a body which may be rendered incandescent are employed increase the light-giving power of the lamp.

In an arc-lamp employing two carbons the effective light is due to the arc formed between the two carbons. In my improved arc-lamp where two carbons and a body which may be rendered incandescent are employed the effective light is due to the arc formed between the angularly-disposed adjustable carbons and to the incandescence of the third carbon or other body.

The accompanying drawings show my invention as embodied in an alternating arc-lamp employing three carbons.

Figure 1 is a vertical section on the line 11 of Fig. 2 with the controlling-magnet connected in shunt. Fig. 2 is a plan view. Fig. 3 is a side view, looking from the left, of the

top of the lamp. Fig. 4 is a vertical section 50 on the line 4 4 of Fig. 2. Fig. 5 is a section corresponding to Fig. 4 with the controlling-magnet arranged for a series connection.

In the drawings, A represents the base-plate of the lamp. Suitably supported above the base-plate is a controlling-magnet B. This magnet in Figs. 1 to 4 is shown as connected in shunt with the leads C D and in Fig. 5 for connection in series with the leads C D.

Pivotedly mounted in brackets E, depending from opposite sides of the magnet B, Fig. 1, or at the ends of a horizontal arm F, carried by a bracket G, projecting upward from the top of the magnet B, are the armatures H I. Secured to the lower curved ends of the armatures H I and angularly disposed as regards each other are the carbon-holders J K. Carried in these carbon-holders are the carbons L M.

Depending from the bracket G, situated 70 above the magnet B, is a rod N, to the lower end of which is connected a third holder, O, carrying a carbon or other body P, which may be rendered incandescent. Projecting horizontally from the top of the rod N, Fig. 75 1, are stops Q, which serve to limit the inward movement of the armatures H I.

Pivotedly connected to each of the carbon-holders J K are the air dash-pots R S, which serve to retard the movement of the armature H I. The carbon-holders J K are respectively connected in shunt, Figs. 1, 2, 3, and 4, (in series, Fig. 5,) with the leads C D through the contact-plates T. The rod N, holder O, and body P are not connected in 85 the lamp-circuit.

Depending from the base of the lamp is a threaded annulus U, which coacts with a similar annulus V, which serves as a support for the oblong inclosing globe W. The operating mechanism on the top of the lamp is covered by a casing X. The lamp is supported by means of a pivoted bail Y.

The operation of the lamp will be readily understood.

In the construction shown in Fig. 1 the carbons L M, the lamp being a shunt-lamp, are normally separated. When a current is turned

on to the lamp, the armatures H I are uniformly magnetized and repel each other, thereby drawing the lower end of the carbons toward each other and into contact with the third carbon or other slightly conductive body which may be rendered incandescent to strike the arc. When the arc is struck, a portion of the current is diverted from the magnet B, which partially demagnetizes the armatures H I and permits them to approach each other, thus regulating the distance between the carbons L M as the carbons are consumed.

In the construction shown in Fig. 5 the carbons L M are normally in contact, and when the current is sent through the magnet B the armatures H I, as in the case of the shunt-lamp, repel each other, but, owing to their having a different pivotal position, serve to draw the carbons L M apart, and thus strike the arc. When the arc is formed, the current sent through the magnet B is decreased, the armatures H I partially demagnetized, which allows them to approach each other as before, and thus regulate the distance between the carbons as the carbons are consumed. When the arc is formed between the carbons L M, the body P is heated, rendered incandescent, and its conductivity increased. The body P when rendered incandescent radiates light and also serves, by reason of the conductivity of the body, to decrease the resistance between the carbons L M, and thus aid in the regulation of the lamp, and, further, by reason of the light emitted from the incandescence of the body P, to in a measure regulate, or, in other words, cover, the variations in light emitted from the arc between the carbons L M and due to their relative movement in feeding.

I wish to have it understood that my improved arc-lamp may be used with but two carbons or two carbons and a body which may be rendered incandescent—such, for instance, as carbon, carbon and clay, metal and clay, slightly conductive material composed of the refractory earths, such as thorium cerium, &c.—and, further, that the mechanism shown and described for effecting the relative movement of the carbons L M may be varied without departing from the intent of my invention.

Having thus described my invention, I claim—

1. An electric-arc lamp embodying in its construction, a solenoidal magnet, a pair of armatures situated and movable within the cavity of said solenoid, and a pair of carbons carried by said armatures and angularly disposed as regards each other.

2. An electric-arc lamp embodying in its construction, a solenoidal magnet, a pair of armatures situated within the cavity of said solenoid, but pivoted exterior thereto, and a pair of carbons carried by said armatures and angularly disposed as regards each other.

3. An electric-arc lamp embodying in its construction, a solenoidal magnet, having its tubular cavity arranged vertically, a pair of armatures situated in said tubular cavity, and a pair of carbons carried by said armatures and angularly disposed as regards each other. 70

4. An electric-arc lamp embodying in its construction, a solenoidal magnet having its tubular cavity arranged vertically, a rod and a pair of pivoted armatures situated in said tubular cavity, and a pair of carbons carried by 75 said armatures and angularly disposed as regards each other.

5. An electric-arc lamp embodying in its construction, a solenoidal magnet, a bracket situated over the magnet, a rod or holder depending from the bracket, a pair of movable armatures arranged on each side of the rod or holder, and within the cavity of the solenoid, and a pair of angularly-disposed carbons carried by said armatures. 80 85

6. An electric-arc lamp embodying in its construction, a solenoid, a bracket arranged over the cavity of the solenoid, a rod or holder depending from said bracket, a pair of armatures one on each side of said rod or holder, 90 and pivoted exterior to the magnet, carbon-holders depending from said armatures, and carbons in said holders.

7. An electric-arc lamp embodying in its construction, a solenoidal magnet, a bracket 95 over the magnet, a holder depending from the bracket, a fusible body carried by said holder, a pair of armatures on each side of said holder and pivoted exterior to said solenoid, a holder carried by each armature, and a carbon carried 100 by each holder.

8. An electric-arc lamp embodying in its construction, a solenoidal magnet, a bracket over the magnet, a holder carried by the bracket, insulated stops mounted on the holder, 105 a pair of armatures on each side of said holder and pivoted exterior to the solenoid, a holder carried by each armature, and a carbon carried by each holder.

9. An electric-arc lamp embodying in its 110 construction, a solenoidal magnet, a pair of armatures situated and movable within the cavity of said solenoid, a pair of carbons carried by said armatures and angularly disposed as regards each other, and a fusible body situated 115 between said carbons.

10. An electric-arc lamp embodying in its construction, a solenoidal magnet, a pair of armatures situated and movable within the cavity of said solenoid, a pair of carbons carried 120 by said armatures and angularly disposed as regards each other, and a third carbon body interposed between said carbons.

11. An electric-arc lamp embodying in its construction, a solenoidal magnet, a pair of 125 pivoted armatures mounted in the interior of the magnet, carbon-holders carried by said armatures, carbons in said carbon-holders, and

means for checking the movement of the armatures.

12. An electric-arc lamp embodying in its construction, a solenoidal magnet, a pair of armatures within said magnet, means for limiting the inward movement of the upper ends of said armatures, a pair of carbons mounted on the lower ends of said armatures, and means

for dampening the movement of said armatures.

In testimony whereof I affix my signature in the presence of two witnesses.

FREDERIK SINDING-CHRISTENSEN.
